UNITED STATES PATENT OFFICE.

PAUL A. BANCEL, OF NUTLEY, NEW JERSEY, ASSIGNOR TO INGERSOLL-RAND COMPANY, OF JERSEY CITY, NEW JERSEY, A CORPORATION OF NEW JERSEY.

SURFACE CONDENSER.

Application filed December 17, 1925. Serial No. 76,052.

This invention relates to surface condensers of the type having a plurality of water conducting cooling tubes extending across a steam chamber and provided with heads at the inlet and discharge ends of the condenser to supply cooling water to the tubes and to receive it therefrom.

One of the objects of the invention is to provide an arrangement of cooling water supply pipes and a blow-off for the inlet head which is adapted to clear fouling material from the entrance of the water tubes.

In the drawing forming part of the specification and in which similar reference characters refer to similar parts—

Figure 1 is a side elevation of a condenser constructed in accordance with the practice of the invention,

Figure 2 is a plan view of the condenser shown in Figure 1,

Figure 3 is an elevation of the condenser in Figure 1 looking from the water inlet end toward the water outlet end, and

Figure 4 is a side elevation of a modification of the invention, parts being broken away to show the internal arrangement of the tubes and the water connection for the devaporizer.

Referring to the drawings and more particularly to Figures 1, 2 and 3, the condenser comprises a shell 10 within which there are arranged a plurality of steam condensing tubes 11 horizontally disposed across the path of the steam entering the condenser shell through a steam inlet 12. The condenser may be provided with a suitable condensate outlet (not shown). The tubes 11 are adapted to conduct cooling water from the water inlet head 13 to a discharge head 14 and are suitably sealed against leakage into the casing 10 in a tube sheet 15 at the inlet 13 and the tube sheet 16 at the discharge head 14.

The water supply pipe is suitably connected to the inlet head 13 preferably at the side (Figure 2).

The discharge pipe 18 is connected with the discharge head 14 to conduct the water from the discharge head to a suitable container (not shown).

Condensers of this type are sometimes constructed with groups of tubes 11 separated by partitions 18 in the inlet head and discharge head 13 and 14 respectively. In such cases more than one supply pipe

17 are employed as in the present instance in which two supply pipes 17, and two discharge pipes 18 are shown being adapted to carry off the discharge water.

The condenser illustrated in the drawing is provided with a pair of evaporizers 19 for the uncondensable gas and vapor from the condenser. Water is supplied to the devaporizers 19 from the main supply pipe 20 through pipes 21 and a U connection 22. The water discharged from the cooling system of the devaporizers is conveyed through a pipe 23 to a lower chamber 24 in the inlet head 13 and then through the lowest bank of cooling tubes 11 to a compartment 25 in the discharge head 14. A pipe connection 26 is provided from the compartment 25 to the main discharge pipe 27.

Separate valves 28 and 29 are provided to control the flow of cooling water from the main supply pipe 20 to the upper and lower compartments in the inlet head 13 respectively. Similar valves 30 and 31 are provided to control the discharge of cooling water from the upper and lower compartments in the discharge head 14 into the main discharge pipe 27.

In operating a condenser of the type described, usually the cooling water is not pure and often contains slime and other fouling material which on entering the inlet head 13 clogs the entrance to the tubes 11 at the tube sheet 15. One of the objects of the invention is to enable the tube sheet to be cleaned by the action of the cooling water in the inlet head 13. To this end there is provided a drain or blow-off pipe preferably disposed at the side of the head 13 and provided with a connection 33 to each compartment in the head 13. The valves 34 are provided at the connection to regulate the water discharge through the pipe 32. The arrangement shown is adapted to permit any compartment of the head 13 to be drained and cleaned without interfering with the operation of the condenser; for instance if it is desired to clean the upper compartment of the head 13 the upper valve 28 is closed and the upper valve 34 to the drain 32 is opened. The valve 30 at the discharge end may also be closed permitting the water in the upper bank of tubes 11 to run out of the compartment and tubes thereby flushing the slime, leaves or other fouling material

110 into the discharge pipe 27. In order to per-

mit a more rapid flow of water into the drain 32, there may be provided a vent 35 and air valves 36 at each discharge pipe 18. Upon opening the valve 36 air is permitted to enter as the water is displaced in the inlet and discharge heads 13 and 14. If the mere draining of the inlet head is not sufficient to clear out all of the fouling material the inlet valve 28 may be opened permitting water to flow across the face of the tube sheet 15 to insure thorough cleansing of said tube sheet and to flush the inlet head. The lower compartment of the inlet head 13 may be cleansed in the same manner.

Figure 4 shows a modification in which the condenser is provided with a shell or casing A into which steam is admitted through the inlet B to be condensed by the cooling tubes C preferably extending longitudinally in the casing A. Water is supplied to the cooling tubes C from a water head D which may be provided with partitions E and F to divide the tubes C into groups, those in the uppermost group being more active in condensing and those in the lower groups being less active since at these depths the proportion of steam to uncondensable air is less. The tubes C at their ends are sealed from the casing A by means of a tube sheet G into which the tubes C are expanded or otherwise sealed to prevent leakage of water from the water head D into the interior of the casing A. Water is supplied to the inlet head D through a pipe H which branches in- to two inlet pipes J and K and are provided with valves L and O respectively to regulate the amount of water flowing to the upper and lower compartments respectively. The pipes J and K enter the water head D at the side and preferably adjacent the tube sheet G. Normally cooling water flows from the inlet head D through the tubes C and thence into a discharge head P provided with discharge pipes Q and R provided with the regulating valves S and T respectively and thence into a main discharge line U to a suitable cooling tank (not shown).

Means are provided to direct the stream of water at relatively high velocity across the tube sheet G. To this end blow-offs are provided comprising the pipes V and W for the upper and next lower compartment respectively of the water head D, which join in a common pipe X leading to the main discharge pipe U. The blow-off pipes V and W are provided with suitable valves Y and Z respectively to control the flow. Thus either compartment may be blown off separately if desired. The condenser in Figure 4 is provided with one or more devaporizers b and c for the uncondensable gases drawn from the casing A. The devaporized gases may be exhausted by means of a vacuum pump (not shown) connected to the outlet pipes e and d respectively. Cold water for

the cooling system of the devaporizers b and c may be supplied through the pipe X, there being strainers F at the entrance to the devaporizers. Preferably the strainers f are cylindrical and open at both ends and inclosed within suitable boxes g so that when a valve h is opened water may flow out through the pipe X across the strainers f and into a pipe i to the discharge line U. Normally when the valve h is closed water will flow through strainers into the devaporizers b and c and thence through a common conduit k into the lowermost compartment in the inlet head D through tubes C associated therewith into a discharge line U. Water may be supplied to the pipe X for the devaporizers b and c from either of the upper two compartments in the inlet head D. Normally in operating a condenser of this type, the lower compartments should be supplied with less water than the upper compartments since the upper compartment performs the greater part of the steam condensation. Therefore, it may be advisable to close the valve Y and open the valve Z for supplying water to the devaporizer. Vents q and r are provided in the discharge pipes Q and R respectively to permit air to enter the tubes and heads of the condensers to fill the space normally occupied by the cooling water. The vents q and r are provided with hand operated valves t and u, respectively, to control the vents.

I claim:

1. A surface condenser comprising a casing, water tubes within the casing, an inlet head for the water tubes having a tube sheet sealing the water from the casing, and means for isolating certain quantities of water for reversing the flow of the isolated water through the water tubes to clean the tube sheet.
2. A surface condenser comprising a casing, water tubes within the casing, an inlet head for the water tubes having a tube sheet sealing the water tubes from the casing, a discharge head for the water tubes, means for reversing the flow of water through the tubes and for directing the flow of water across the tube sheet to clean the tube sheet including a drain pipe for said inlet head, and a vent in said discharge head.
3. A surface condenser comprising a casing, a plurality of cooling tubes in the casing, an inlet head for said tubes, a tube sheet at the inlet head, a water supply pipe for the inlet head for admitting water parallel to the tube sheet and a drain pipe for the inlet head disposed opposite the supply pipe with respect to the tube sheet.
4. A surface condenser comprising a casing, water tubes within the casing arranged in groups, an inlet head for the water tubes having a tube sheet sealing the water tubes from the casing, and means for isolating

certain quantities of water in certain groups of said tubes for reversing the flow of the isolated water through the tubes to clean the tube sheet, and a drain pipe for conveying such water from the inlet head.

5. A surface condenser comprising a casing, water tubes within the casing arranged in groups, an inlet head for the water tubes having a tube sheet sealing the water tubes from the casing, a discharge head for the water tubes, and means for isolating certain quantities of water for reversing the flow of such water through the tubes to clean the tube sheet including drain pipes for said inlet head and a vent in said discharge head.

6. A surface condenser comprising a casing, a plurality of cooling tubes in the casing arranged in groups, an inlet head for said tubes, a tube sheet at the inlet head, water supply pipes for the inlet head for admit-

ting water thereto parallel to the sheet, drain pipes for the inlet head disposed opposite the supply pipe with respect to the tube sheet, and means for isolating certain groups of tubes and for reversing the flow of such water through said groups of isolated tubes to clean the tube sheet.

7. A surface condenser comprising a casing, a plurality of cooling tubes in the casing 30 an inlet head for said tubes divided into separate sections, a water supply pipe at the inlet head for admitting water parallel to the tube sheet and drain pipes at the inlet head disposed opposite to the supply 35 pipes with respect to the tube sheet and means to cause the water to flow across the tube sheet and certain sections of the inlet head separately from other sections.

In testimony whereof I have signed this 40 specification.

PAUL A. BANCEL.
